JOHN WALTER BRAUNSCHWEILER, OF PALO ALTO, CALIFORNIA.

GAME.

1,275,210.

Specification of Letters Patent.

Patented Aug. 13, 1918.

Application filed March 22, 1918. Serial No. 224,036.

To all whom it may concern:

Be it known that I, JOHN WALTER BRAUNSCHWEILER, a citizen of Canada, residing at Palo Alto, in the county of Santa Clara and State of California, have invented certain new and useful Improvements in Games, of which the following is a specification.

This invention relates to games in puzzle form, and consists of a base in the form of a fort having railway tracks and guns mounted thereon.

The base is triangular in shape with two of its corners extending outwardly a short distance. Forts are positioned on the two short sides of the base, one fort having a large gun and the other fort having a smaller gun. Two cars of ammunition have been placed at the wrong guns and the principal object of the game is to place the cars 20 at their right guns by the use of the locomotive, without running the locomotive on the turn-table.

A further object of the invention is to provide a game which will require considerable study to work out. This and other objects will be more apparent as the invention is more fully described in the following specifications.

With these and other objects in view, the invention consists in the construction, combination and arrangement of parts as will be hereinafter fully described, illustrated in the accompanying drawings, and pointed out in the claims hereunto appended.

Figure 1 is a top plan view of the game showing positions of the two guns, and the two cars placed in their wrong places.

Fig. 2 is an elevation showing how the base may be folded together so that the same may be put in a box or other receptacle when not in use.

Fig. 3 is a sectional view on the line A—A of Fig. 1, and

Fig. 4 is a side elevation of one of the gun forts showing the means for fastening same to the base.

Referring to the drawings like numerals designate like parts in the various drawings.

B designates the base, being triangular in shape to represent the base of a fort. The two corners 5 and 5' of the base extend outwardly and may be folded in on suitable hinges 6 as shown in Fig. 2 so that the same 55 may be folded up and placed in a receptacle or box when not in use.

7 represents the main line track which is commonly used in connecting lines of forts of this character, and 8 and 9 are branch tracks which are used for running the cars 60 of ammunition to the forts containing the guns. 10 is a turn-table which is placed at the two meeting ends of the branch tracks so that the cars of ammunition may be turned onto either track. 65

C designates a fort holding a large gun, and D designates a fort holding a smaller gun. These forts are fastened to the main base B by metallic braces or hooks 11 which fit into sockets 12 placed on the side of the 70 main base.

C' designates a car holding large ammunition for the larger gun, and D' designates a car holding ammunition for the smaller gun. These cars are here shown on the 75 branch tracks, the car D' holding the small ammunition being placed at the large gun, and the car C' holding the large ammunition being placed at the small gun. E designates a locomotive which is here shown on 80 the main line and is adapted to be used in shunting the two cars holding the ammunition to their right places.

With reference to Fig. 3, the tracks are formed of flat pieces of metal which are fastened to the main base by suitable screws 14 and the tracks are adapted to project over a groove 15 in the main base. 85

The locomotive and cars are provided with a block 16 which has outwardly extending flanges 17 so that same may run in the groove 15 and be held from running off the track by the extending portion of the track. 90

In describing the operation of the invention, the object is to place the cars C' and D' 95 at their respective places by the use of the locomotive, without running the locomotive on the turn-table, and have the locomotive placed back on the main track when finished.

The locomotive is operated by the hand 100 and is taken back to the corner 5', switched onto the branch track 9 and pushes the car C' onto the turn-table 10. The locomotive is then brought back and over to the branch track 8, pushes the car D' up and connects 105 the same with the car C', pulls the two cars back to the corner 5 and then pushes the same across to the corner 5'. It then leaves the car C' resting on the corner 5', pulls the car D' across to the corner 5, then pushes it 110 along the branch track 8 and leaves it on the turn-table. The locomotive is then brought

back to the corner 5, taken across and up the branch track, takes the car D' off the turn-table, pulls it back and leaves it at its proper place which is behind the smaller gun. 5 After leaving it there, the locomotive is then brought down and connected with the car C' which has been standing on the corner 5'. The car C' is then pulled across the main line to the corner 5, pushed up the side track 8 and placed in its proper place which 10 is behind the large gun. The locomotive is then brought back and left resting on the main line.

From the foregoing it is thought that the 15 construction of my invention will be clearly understood, and therefore a more extended explanation has been omitted.

What I claim as new, is,—

1. A game representing a fort consisting 20 of a base triangular in shape and having its two corners adapted to be hingedly connected and turned so that same may be placed in a small receptacle, a main line track running across one of the straight sides of said fort having two branch tracks having a turn-table at their meeting ends, two smaller forts 25 mounted on said base, one holding a large

gun, the other a small gun, cars to hold ammunition for said guns adapted to be run on the said tracks, a locomotive for operating 30 said cars, and means for holding said locomotive and cars on the tracks.

2. A game of the character described comprising a base of triangular shape in the form of a fort having a main line and branch 35 lines running therefrom, a turn-table at one of the angles of the base, two guns of different sizes fastened on each side of said base and two cars adapted to be operated by a locomotive, one of said cars holding large 40 ammunition for the large gun and the other car holding small ammunition for the small gun, said cars being placed in their wrong positions and adapted to be placed at their correct positions by the use of the locomotive 45 without running the said locomotive on the turn-table.

In testimony whereof I affix my signature in the presence of two witnesses.

JOHN WALTER BRAUNSCHWEILER.
